UNITED STATES PATENT OFFICE.

JOHN GONDEK, OF ST. PAUL, MINNESOTA.

PRINTING APPARATUS.

1,347,505.

Specification of Letters Patent. Patented July 27, 1920.

Application filed September 1, 1917. Serial No. 189,303.

To all whom it may concern:

Be it known that I, JOHN GONDEK, a citizen of the United States, residing at St. Paul, in the county of Ramsey and State of Minnesota, have invented certain new and useful Improvements in Printing Apparatus, of which the following is a specification.

My invention relates to an improved apparatus for printing by which inequalities 10 in the printing faces of the type are compensated for, thus making an evenness in the printing operation not possible with the ordinary apparatus and methods.

The object of my invention is to provide 15 an apparatus for all grades of commercial printing done on cylinder type press dispensing with the hand make ready.

In carrying out my invention, I employ 20 a composition covering or blanket for the first transfer cylinder, "B," which receives an impression from the type. This covering is built up as follows: a heavy layer of specially prepared soft, yielding printer's roller material 3. On this, in turn, is cast a 25 fine layer of specially prepared hard and perfectly smooth material 3', as celluloid, which receives an impression from the type and a printing cylinder c to which this impression is transferred from the first cylinder, the impression being transferred to 30 the paper from the second cylinder in the accompanying drawing forming part of this specification.

Figure 1 is an end elevation of a printing 35 press embodying my features of invention,

Fig. 2 is a top view of a portion of the bed motion,

Fig. 3 is a vertical section through the bed motion,

Fig. 4 is a section through the printing and transfer cylinders,

Fig. 5 is a detailed view of an actuating gear for the bed motion,

Fig. 6 is a side elevation of a printing 45 press embodying my features of invention, and

Fig. 7 is a side elevation of the bed motion.

Referring to the drawings, A represents 50 the frame work of a printing press suitably supporting a slidable type bed 2. Journaled above the type bed is a horizontal cylinder B to receive the printing impression from the type in the type bed. A cyl-

inder C journaled along side of and in contact with the cylinder B to receive the impression therefrom and constitute the transfer or printing cylinder and a feed cylinder D is journaled along side of and in contact with the printing cylinder C. The impression receiving cylinder B is provided with a suitable composition or equivalent yielding covering 3 to receive the printing impression and equalize the same, and the cylinder C is formed with a suitable covering 4 to 65 constitute a printing surface. The cylinders B, C and D are operated from the driving shaft E through the medium of the gearing 5.

The driving shaft E may be provided 70 with a driving pulley 6 to be operated from a suitable source of power not shown.

The type bed is adapted to be reciprocated by the following described mechanism:

Projecting downwardly from the type bed 75 is a frame F. Having central pivotal support 7 in the frame F is a rack frame 8, said frame 8 supporting from its upper end a downwardly directed rack bar 9 and from its lower end an upwardly directed rack bar 80 10. Between the rack bars 9 and 10 is positioned a gear 11 supported upon an inner end of a shaft 12, said shaft being journaled in the frame work and at its outer end having driving connection 13 with the driving 85 shaft E. In the operation of the machine the tilting of the frame 8 alternately brings the racks 9 and 10 into engagement with the gear 11 to oppositely reciprocate the type bed.

The frame 8 is tilted upon its pivot by means of a lever arm 14 having fulcrum support 15 in the base of the machine, the upper end of said lever arm having operative engagement with a lug 16 projecting 95 downwardly from the frame 8. The lever arm 14 has link connection 17 with a second lever arm 18 having fulcrum support 19 in the base of the machine. The free end of the lever arm 18 is engaged by a cam wheel 20 carried by a horizontal shaft 21 journaled in the machine frame-work. The shaft 21 is operatively connected by the train of gearing 13 and 22 with the driving shaft E.

For the purpose of co-operating with the gear 11 in actuating the type bed, I provide a pair of arms 23 and 23', each of

said arms having pivotal support 24 upon the rack frame 8. The said arms at their inner ends have toothed engagement 25 so that the turning of one arm will turn the other. Each arm at its outer end carries an outwardly projecting pin 26. The gear 11 as shown in Fig. 5 is formed upon one side and adjacent to its outer edge with a cam 27 adapted to engage the pin 26 of one of the bars 23 or 23^a, as the gear passes beyond the rack, to continue movement of the type bed. The bar 23 or the bar 23^a, as the case may be, is turned to bring its pin 26 into the path of the cam 27 through the medium of an arm 28 carried by the arm 23 and projecting rearwardly therefrom. The free end of the arm 28 carries a roller 29 traveling in connection with a guide 30 supported by the frame work of the machine. As the roller 29 travels over the ends of the guide 30 the arms 23 and 23^a will thereby be turned to lower the pins 26 into the pathway of the cam 27. The engagement of the cam 27 with one of the pins 26 will swing its supporting arm in the arc of a circle as shown in Fig. 6, shoving the type bed to the end of its movement, and at the same time slowing up the movement so as not to make too abrupt a stop.

Ordinarily in carrying out my invention I provide the transfer cylinder, "B," with a suitable covering, 3, of a heavy layer of soft yielding printer's roller material. This in turn is covered with a fine layer of hard and perfectly smooth material 3', as celluloid to receive the impression from the type and provide the transfer or printing cylinder

with a relatively hard covering, 4, as of hard rubber.

By means of my improved printing means and methods, I compensate for the inequalities in the type to an extent not possible with the ordinary employed methods and I secure a particularly clear cut printing effect.

The impression cylinder will be raised in any desired manner to allow the return of the type bed, as by means of the eccentric mechanism 31.

I claim:

1. In a printing apparatus of the class described, a transfer cylinder, a yielding composition covering therefor, and a relatively hard sheet surfacing for said covering.

2. In a printing apparatus of the class described, a transfer cylinder having a yielding composition facing, a relatively hard non-ink absorbing covering for said facing and a transfer cylinder arranged in co-operation with said transfer cylinder.

3. In a printing apparatus of the class described, a transfer cylinder, a yielding composition facing therefor, a relatively hard, thin and smooth surfaced covering for said facing, and a transfer cylinder arranged in co-operation with said transfer cylinder.

In testimony whereof I affix my signature in presence of two witnesses.

JOHN GONDEK.

Witnesses:
